UNITED STATES PATENT OFFICE.

OVERTON WINSTON, OF MINNEAPOLIS, MINNESOTA.

ELECTRIC HEADLIGHT.

1,328,607.

Specification of Letters Patent. Patented Jan. 20, 1920.

Application filed June 28, 1916. Serial No. 106,373.

To all whom it may concern:

Be it known that I, OVERTON WINSTON, a citizen of the United States, residing at Minneapolis, in the county of Hennepin and 5 State of Minnesota, have invented certain new and useful Improvements in Electric Headlights; and I do hereby declare the following to be a full, clear, and exact description of the invention, such as will enable 10 others skilled in the art to which it appertains to make and use the same.

My present invention relates to headlights and has for its object to provide a novel arrangement of light dimming surface and 15 shifting light source within a concave reflector, whereby, even when high power light bulbs are employed, blinding is prevented by dimming of the main portion of that part of the direct light beam that is 20 above the axis of the reflector. The shifting light source is preferably a two-filament light bulb and the light dimming surface is preferably applied directly to the globe of the light bulb.

25 In the accompanying drawings which illustrate the invention, like characters indicate like parts throughout the several views.

Referring to the drawings:

Figure 1 is a front elevation of the head 30 light embodying my invention;

Fig. 2 is a vertical section taken on the line $x^2 x^2$ of Fig. 1;

Fig. 3 is a horizontal section taken on the irregular line $x^3 x^3$ of Fig. 1;

35 Fig. 4 is a view corresponding to Fig. 1, but illustrating a slightly modified construction;

Fig. 5 is a vertical section on the line $x^5 x^5$ of Fig. 4;

40 Fig. 6 is a horizontal section taken on the irregular line $x^6 x^6$ of Fig. 4;

Fig. 7 is a view corresponding to Figs. 1 and 4, but illustrating a further slightly modified arrangement;

45 Fig. 8 is a vertical section taken on the line $x^8 x^8$ of Fig. 7; and

Fig. 9 is a horizontal section taken on the irregular line $x^9 x^9$ of Fig. 7.

Referring first to the construction illustrated in Figs. 1, 2 and 3, the numeral 10 indicates a concave reflector of parabolic or similar form, and the numeral 11 indicates an electric light bulb having two filaments, the hot spots of which are indicated 55 at a and b . This light bulb is, or may be of the character disclosed in my prior appli-

cation S. N. 86,852, filed March 27, 1916, and entitled "Headlights," and by reference to which it will be noted that either of the two filaments may, at will, be utilized as the 60 light source.

The point a may be assumed to be the focal center of the reflector 10, while the point b is offset above the point a and located forward of the same. On its upper 65 forward portion, the globe of the light bulb 11 is provided with a translucent portion 12 herein designated as a light dimming surface and which may be formed in various different ways, as by frosting, sanding or 70 coloring. The upper margin of this light dimming surface 12 follows a curved line that is intersected by lines above a horizontal drawn from the hot spot b to the upper and side edge portions of the reflector 75 10. The lower margin of the said light dimming surface 12 is in a horizontal plane that intersects the said point b . The remaining portion of the globe of the bulb is clear. With this arrangement, when the light 80 source is at b , that portion of the light beam that is produced by direct light rays and is above the horizontal plane of the said point b will be dimmed and blinding effect is thereby prevented. When the light source 85 is at a , the upper portion of the direct ray beam will be slightly upward and there will be a somewhat greater direct ray projection than when the said light source is at b , but a very considerable part of the upper portion 90 of the direct ray beam will be dimmed. The light source at b gives the best beam projection for city driving, while the light source at a gives the best projection for country driving, or where a longer and less 95 obstructed light beam is desired.

In a two-filament lamp, the filament whose hot spot is indicated at a may have greater candle power than the filament whose hot spot is indicated at b . In this 100 way, also, the desired variation for city and country driving may be further accomplished.

In Figs. 5 to 9, inclusive, parts corresponding to those just above described are 105 indicated by like characters.

In the arrangement shown in Figs. 4, 5 and 6, the axial filament a may be assumed to be at the focal center of the reflector, but the offset filament b is located in a vertical 110 line above the said filament a . The lower margin of the light obstructing surface 12

is in the horizontal plane of the point *b*, and the upper margin of said light obstructing source is on a curved line intersected by radial lines drawn from the said point *b* to 5 the upper and side edge portions of the reflector.

In the construction illustrated in Figs. 7, 8 and 9, the offset filament *b* is located above and to the rear of the axial filament *a*, but 10 the above stated plan of applying the light dimming surface 12 is adhered to.

Of course, in practice, the filaments of the lamp will not be confined to the spots *a* and *b* and there will be some of the less intense 15 rays that do not follow precisely the lines stated, but the general effect is as described.

The term "axis" is herein used in a liberal sense to indicate the approximate central line of the reflector, and regardless of 20 whether or not the said reflector has a true axis of rotation.

It should be further understood that when the light source is shifted to the vertically offset point *b*, there will be a much greater 25 downward deflection of the reflected beam than when the light source is at *a*, and that the effect of this is to throw the greater part 30 of the reflected beam below the axis of the reflector. Otherwise stated, when the light source is at *b*, there will be a greater intensity of light in that portion of the light beam that is below the axis of the reflector, than there is in that portion of the beam that is above the said axis. This 35 shifting, in itself, at least to a very considerable extent, prevents blinding effects by the reflected beam, but does not, of course, prevent blinding effects from the direct beam.

The dimming surface located as described, is therefore of the utmost importance, both 40 when the light source is at *a*, as for long distance projection, and when the light source is at *b*, as for short beam projection. There is, therefore, an important relation 45 between the reflector, the shifting light source and the properly located light dimming surface.

What I claim is:

1. The combination with a concave reflector, of a light bulb within said reflector 50 having two filaments, one in the axis of said reflector and one above the axis of said reflector, said bulb having a light dimming surface, the lower margin of which is in the horizontal plane of said vertically offset 55 filament and the upper margin of which is on the line intersected by lines radiating from said offset filament and intersecting the upper marginal portion of said reflector.

2. The combination with a reflector, of 60 a two-filament light bulb having the hot spot of one of its filaments in the axis of said reflector and having the hot spot of its other filament above said axis, and a light dimming surface applied on the globe 65 of said bulb with its lower edge above the horizontal plane of said axis and forward of vertical lines intersecting the hot spots of said two filaments.

In testimony whereof I affix my signature 70 in presence of two witnesses.

OVERTON WINSTON.
